REFRIGERATING APPARATUS

Filed Feb. 15, 1929

UNITED STATES PATENT OFFICE

MATSON C. TERRY, MILTON KALISCHER, AND THOMAS A. BUCKLEY, OF MANSFIELD, OHIO, ASSIGNORS TO WESTINGHOUSE ELECTRIC AND MANUFACTURING COMPANY, A CORPORATION OF PENNSYLVANIA

REFRIGERATING APPARATUS

Application filed February 15, 1929. Serial No. 340,273.

This invention relates to refrigerating apparatus and particularly to that type of apparatus which is designed for household or shop use.

5 An object of the invention is to provide an evaporator for such an apparatus which shall be durable, rigid, and easily assembled.

Another object is to provide an evaporator which shall have smooth and easily cleaned 10 exposed surfaces.

A further object is to provide a cooling unit having a small volume of brine contained therein as compared with a large amount of exposed surface.

15 A still further object is to provide an evaporator, within the confines of which may be located either the expansion valve, or thermostat, or both, thereby obviating the necessity of mounting these instruments on the outside of the evaporator where they are liable to be damaged in handling and shipping, and where they interfere with the smooth, unbroken, cleanable surface of the 20 evaporator.

25 Another object of this invention is to provide an evaporator having a particularly effective freezing compartment, and provided with means to assist in the rapid transfer of heat from the substance to be frozen to the refrigerant coils.

30 The invention further provides an assembled refrigerating apparatus, horizontally removable from the refrigerator cabinet, and in which the evaporator is suspended below 35 the heat-dissipating unit in such a manner that heat transfer between the evaporator and its suspending means, and the base to which the suspending means is attached, is effectually prevented.

40 More specifically, a suspending means is provided, a portion of which is of insulating material, thereby providing a seal against heat transfer between the evaporator and the supporting base.

45 Other objects and advantages of the invention will be readily apparent from the following description and accompanying drawings, wherein,

50 Figure 1 is a perspective view of a mechanically-cooled refrigerator cabinet with

the refrigerating apparatus in operative position.

Fig. 2 is a perspective view of the removable portion of the upper front bracing strip.

Fig. 3 is a perspective view of the improved 55 evaporator, and the base from which it is suspended.

Fig. 4 is a rear elevation of the evaporator showing the thermostat and expansion valve in operating position.

Fig. 5 is a sectional view of the evaporator 60 taken on the line V—V of Fig. 4 and looking in the direction of the arrows.

Fig. 6 is a vertical sectional view through one of the insulating members for attaching 65 the evaporator to the supporting base, and

Fig. 7 is a perspective view of the finishing strip.

Referring to the drawings, wherein is shown a specific form of the invention, 10 designates a refrigerator cabinet having a storage compartment 11 adapted to be closed by doors 12.

15 The refrigerating apparatus adapted to be applied to this cabinet comprises a base 13 on which is supported a sealed motor-compressor unit 14 and a condenser 15. A motor control switch box 16 may also be supported on the base.

20 A cooling unit 17 is suspended from the base 13 by means of two L-shaped pipes 18, the cooling unit being attached to the long arm of each of said pipes by means of bolts 19 which pass upwardly through lugs 20 welded to the evaporator by flanges 21. The 25 bolts pass through openings provided in the lower surfaces of the pipe and are retained by nuts 22. Openings 23 are provided in the upper surface of the pipes above the bolts to enable the nuts to be manipulated.

30 The short arm of each L-shaped pipe is welded or otherwise fastened to a plate 24. A cylindrical block 25 of insulating material, and provided with an opening 26 is fastened to the upper side of plate 24 by means of 35 screws 27. The opening 26 coincides with the opening 28 in the hollow supporting pipe, thereby permitting the passage of conduits therethrough. The insulating blocks are fastened to the base by means of bolts 29 40

which project upwardly through the block and base 14 and through a retaining plate 30. Nuts 31, provided on bolts 29 retain the blocks firmly against the base.

5 The cooling unit comprises an outer metallic shell 32, open at both its ends. This outer shell may be provided with longitudinal corrugations 33 to increase its rigidity. One or more pressed metal pots 34 is inserted within the shell and soldered or welded thereto at an outer edge thereof, as indicated at 35. Two such pots are indicated in the drawings, although it will be apparent that any number may be provided, depending entirely on the 10 size of evaporator desired. These pots serve as a freezing compartment for receiving trays containing articles to be chilled or frozen. Longitudinal projections 36 are pressed inwardly into the walls of these pots. 15 These projections serve as supports or slides for the ice-making trays 37.

A pressed metal pot 38 is inserted into the opposite end of the shell 32 and is welded or soldered to the shell as indicated at 39. This 20 pot provides a recess for receiving the thermostat 40 and expansion valve 41. Refrigerant expansion coils 42 are wrapped about the pots 34 and 38 in the space between the walls of the pots and the walls of the shell 32. A 25 removable plug 43 is provided in the outer shell for permitting the space between the pots and shell, and surrounding the refrigerant expansion coils to be filled with a cold storage solution, for example alcohol and 30 water.

In assembling the cooling unit, the free 35 ends 46 and 47 of the coil 42, which has previously been formed on a suitable mandrel, are passed through openings provided in an enlarged portion 48 of pot 38. The formed coil and pot are then inserted in the shell 32. Pots 40 34 are then inserted within the shell and within the coil 42, which has substantially the contour of the shell 32. The edges of the shell and pots are then welded, as indicated 45 at 35, 39 and 44.

One end of the expansion coil is connected 50 to the expansion valve 41 by a conduit 49, while the other end is connected to a conduit 50. A conduit 51 is provided for carrying 55 refrigerant from the condenser 15 to the expansion valve, and conduit 50 carries expanded refrigerant from the expansion coil to the compressor. Both these conduits pass through one of the hollow pipes 18, and the opening 26 provided in one of the blocks 25, and thence to the designated apparatus.

A conductor 52 passes from switchbox 16 through the remaining insulating block and 60 hollow L-shaped pipe to the thermostat 40.

A portion 53 of the top front bracing strip of the refrigerator cabinet is made removable (Fig. 2) and is provided with two spaced semi-circular slots 54. Spaced semi-circular 65 slots 55 are likewise provided in the fixed

portion 56 of the bracing strip, so that when the two portions are bolted together, two cylindrical holes extend vertically through the strip for a purpose to be hereafter described.

70 In applying the assembled refrigerating apparatus to the box, the base 13 is slid horizontally on the top of the cabinet until the cylindrical blocks 25 are received in the slots 55. The removable portion 53 of the bracing strip is then bolted to the fixed portion, with its slots 54 encircling the protruding portion of the blocks 25. A finishing strip 57 (Fig. 7) may then be fastened to portion 53. This strip is made of the same material, and has the same finish as the rest of the outer surface 75 of the box.

80 The cooling unit previously described is preferably enameled on its exposed surfaces so that it is smooth and easily cleaned. The projections 36 which are pressed in the walls of pots 34 to serve as slides for the ice trays, contain brine solution when the evaporator is filled through plug 43. Inasmuch as the trays 37 are supported directly by these brine-filled projections, a particularly effective transfer of heat from the tray to the brine and expansion coil is effected and the time required for making ice is materially reduced. A door 58 may be provided on the open ends 85 of the respective freezing compartments to increase the efficiency of the compartments.

90 While we have shown and described a cooling unit having two freezing compartments, it will be apparent that the number 95 which may be used is limited only by the amount of ice desired to be made.

95 Locating the thermostat and expansion valve within the confines of the cooling unit instead of in the customary position on the outer surface thereof, permits the cooling unit to have a smooth unbroken outer surface which may be easily cleaned.

100 It will be apparent from the foregoing description that we have provided an efficient and practical means of suspending a cooling unit from a base within a refrigerator cabinet in such a manner that the base and cooling unit may be horizontally removed from the cabinet without disassembling the apparatus.

105 It will be further apparent that the suspending means provides excellent insulation against heat transfer between the base and the cooling unit.

110 The cooling unit included in this invention is particularly adapted to quantity production as it has relatively few parts and is easily assembled. Furthermore, its freezing compartments are designed to effectively produce ice in a comparatively short time, and its exposed surfaces are so designed as to prevent the accumulation of dirt and foreign matter.

115 While we have shown and described a particular form of the invention, it will be ap-

parent that other forms may be provided, all coming within the scope of the appended claims.

We claim as our invention:

5. 1. A cooling unit comprising a double-walled hollow shell provided with inwardly extending recesses at opposite ends. 70
10. 2. A cooling unit comprising an open ended shell, at least two pots within said shell in back to back relation, and fastened at their outer edges to the shell. 75
15. 3. A cooling unit including a freezing compartment having an opening, and a second compartment having a recess in a direction opposite the opening in the freezing compartment. 80
20. 4. A cooling unit having a freezing compartment at one end thereof, a second compartment at its opposite end, and a pressure-reducing valve in the second compartment. 85
25. 5. A cooling unit having a freezing compartment at one end, a second compartment at its opposite end, a pressure-reducing valve and temperature-responsive device in the second compartment. 90
30. 6. A heat-absorbing unit comprising a brine tank, a freezing compartment in said tank, a second compartment in said tank in back to back relation with the freezing compartment, and expansion coils within the tank and surrounding both said compartments. 95
35. 7. Refrigerating apparatus comprising a heat-dissipating unit mounted on a base and a heat-absorbing unit, the heat-absorbing unit being suspended from, and located beneath and close to, the heat-dissipating unit, but spaced therefrom, conduits interconnecting said units, and a refrigerator cabinet 100
40. having insulated walls defining a storage chamber, the top insulated wall being fixed and integral with the cabinet and forming a heat-insulating portion between the base carrying the heat-dissipating unit, which is supported by the wall, and the heat-absorbing unit located within the storage chamber beneath the wall, means for suspending the heat-absorbing unit from the base, said means including a heat-insulating portion, 105
45. said top insulated wall being provided with a recess at its edge for receiving the insulating portion of the suspending means. 110
50. 8. Refrigerating apparatus comprising a heat-dissipating unit mounted on a base and a heat-absorbing unit, the heat-absorbing unit being suspended from, and located beneath and close to, the heat-dissipating unit but spaced therefrom, conduits interconnecting said units, and a refrigerator cabinet 115
55. having insulated walls defining a storage chamber, the top insulated wall being fixed and integral with the cabinet and forming a heat-insulating portion between the base carrying the heat-dissipating unit, which is supported by the wall, and the heat-absorbing 120
60. unit located within the storage chamber beneath the wall, means for suspending the heat-absorbing unit from the base, said means including a heat-insulating portion, 125
65. but spaced therefrom, conduits interconnecting said units, and a refrigerator cabinet 130

unit located within the storage chamber beneath the wall, means for suspending the heat-absorbing unit from the base, said means including a heat-insulating portion, said top insulated wall being provided with a recess at its edge for receiving the insulating portion of the suspending means, and said interconnecting conduits passing through said insulating portion.

9. Refrigerating apparatus comprising a heat-dissipating unit mounted on a base and a heat-absorbing unit, the heat-absorbing unit being suspended from, and located beneath and close to, the heat-dissipating unit but spaced therefrom, conduits interconnecting said units, and a refrigerator cabinet having insulated walls defining a storage chamber, the top insulated wall being fixed and integral with the cabinet and forming a heat-insulating portion between the base carrying the heat-dissipating unit, which is supported by the wall, and the heat-absorbing unit located within the storage chamber beneath the wall, means for suspending the heat-absorbing unit from the base, said means including a substantially vertical cylindrical heat-insulating portion, the top insulated wall having a substantially vertical groove therein for receiving the insulating portion of the suspending means. 95

10. In a refrigerating apparatus, a base, a heat-dissipating unit mounted on the base, a heat-absorbing unit, means for suspending the heat-absorbing unit from the base, said means comprising a heat-conducting portion and a heat-insulating portion located between the base and the heat-conducting portion, and conduits interconnecting said units, said conduits passing through both said portions. 100

In testimony whereof, we have hereunto subscribed our names this 6th day of February, 1929.

MATSON C. TERRY.
